UNITED STATES PATENT OFFICE.

FRANK RUDOLPH, OF CHICAGO, ILLINOIS, ASSIGNOR TO AMERICAN CAN COMPANY, OF NEW YORK, N. Y., A CORPORATION OF NEW JERSEY.

STATIONARY-CAN DOUBLE-SEAMING MACHINE.

No. 877,375.

Specification of Letters Patent.

Patented Jan. 21, 1908.

Application filed October 30, 1905. Serial No. 284,927.

To all whom it may concern:

Be it known that I, FRANK RUDOLPH, a citizen of the United States, residing in Chicago, in the county of Cook and State of Illinois, have invented a new and useful Improvement in Stationary-Can Double-Seaming Machines, of which the following is a specification.

My invention relates to double seaming machines for seaming the heads or covers upon sheet metal cans, and more particularly to double seaming machines of the kind or class in which the can is held stationary during the seaming operation, and which are specially designed for seaming the covers on filled cans, the can being given no rotatable movement in order to prevent danger of its contents being thrown out, as is the case in machines wherein the can is rapidly rotated during the seaming operation.

The object of my invention is to provide a stationary can double seaming machine of a simple, efficient and durable construction, by means of which covers may be rapidly, cheaply and perfectly double seamed on filled cans.

My invention consists in the means I employ to practically accomplish this object or result; that is to say, it consists, in connection with a can feed table or guide track, along which the cans may be fed or moved, one by one, an intermittently movable endless flexible can feeder or chain having can pusher arms thereon for feeding or moving the cans, one by one, intermittently along the can feed table or track, a vertically reciprocating chuck or plate upon which each can in turn is delivered by the feeder, a pair of horizontally reciprocating can clamping jaws for clamping and centering the can to be seamed with the upper can clamping chuck or plate and with the rotary seaming head, an upper can clamping chuck or plate co-operating with said lower reciprocating chuck or plate to firmly clamp and hold the cover on the can body preparatory to and during the seaming operation, a continuously rotating seaming head carrying a plurality of seaming rollers, each mounted upon a separate vibrating lever hinged to said seaming head, and a continuously rotating can wheel mounted upon the seaming head and rotating independently thereof and at a slightly variant speed to cause the can wheel

to turn slowly in respect to the seaming head and thus cause the cans of the can wheel to 55 operate the several seaming roller levers in proper time and succession.

My invention also consists in the novel construction of parts and devices and in the novel combinations of parts and devices herein 60 shown or described.

In the accompanying drawings, forming a part of this specification, Figure 1 is a front elevation of a stationary can double seaming machine embodying my invention; Fig. 2 is 65 a side elevation; Fig. 3 a detail central vertical section on line 3—3 of Fig. 1; Fig. 4 is a horizontal section on the broken line 4—4 of Fig. 2; Fig. 5 is a detail vertical section on line 5—5 of Fig. 4; Fig. 6 is a detail vertical 70 section on line 6—6 of Fig. 1; Fig. 7 is a detail vertical section on line 7—7 of Fig. 2; Fig. 8 is an enlarged central vertical section of the rotary seaming head and can chucks; Fig. 9 is a partial vertical section on line 75 9—9 of Fig. 11, showing one of the other pair of seaming rollers; Fig. 10 is a detail front elevation of the seaming roller and its operating lever, shown in Fig. 9, and Fig. 11 is a detail section on line 11—11 of Fig. 8, and 80 showing the cam wheel and cams thereon.

In the drawing A represents the frame of the machine, B is the can feed table or guide track along which the cans to be seamed are pushed or fed by the endless can feeder C, 85 preferably consisting of an endless chain, furnished with can pusher arms or projections C¹ and traveling upon pulleys or sprocket wheels C² C³ C⁴. The can feed table B is furnished with a central slot or channel b to receive and accommodate the feeder C, and also with side guides b¹ furnished with transverse slots b² and adjustably secured in place by bolts or screws b³, so that these guides may be placed close together or farther apart as required for operation upon cans of different diameters.

D is the lower vertically reciprocating can chuck fitting in a central opening B¹ in the feed table or track B, upon which each can in turn is delivered by the feeder C, and by which the can is moved upward and clamped against the upper stationary can chuck E in position for being operated upon by the seaming head and seaming rollers or tools. The upper can chuck or plate E is furnished

- with a ring E¹ which fits within the counter-sink x of the cover X of the can X¹.
- F are horizontally reciprocating can body clamping and centering jaws, preferably segmental in form, and having slotted shanks f for adjustably securing the same by bolts f¹ to the slides F¹ which travel in suitable guides F² on the frame of the machine, and by which the can body clamping jaws 10 F are operated to clamp and center each can in turn with the upper chuck E and seaming head G, just before the lower chuck D clamps the can X and its cover X¹ against the stationary upper chuck E.
- 15 G is a rapidly and continuously rotating seaming head rigidly secured to the hollow seaming head shaft G¹, surrounding the hollow stem E² upon which the upper stationary chuck E is supported. The rotary seaming head G carries two pairs of seaming rollers, one pair g g being forming rollers, and the other pair g¹ g¹ finishing rollers, the forming rollers coming first into action to curve or fold the flange x¹ of the cover X about the 20 flange x² of the can body X¹, and the finishing rollers g¹ g¹ coming next into action to finish the formation of the seam and compress its several folds or flanges snugly and closely together. The rotary seaming head G has four 25 lugs or projections G¹¹, preferably formed integral therewith, to which the seaming roller levers g² and g³ are pivotally connected or hinged by suitable pivots g⁴. The seaming tools or rollers g g¹ are rotatably mounted 30 upon their carrying levers g² g³ by suitable studs g⁵ secured in place by set screws g⁶. The operating levers g³, upon which the finishing rollers g¹ are mounted, are preferably furnished with an additional separate piece 35 or adjustable arm g⁷ pivotally connected to the lever g³ by the pivot pin g⁸, the arm g⁷ being additionally and adjustably and yieldingly connected to the lever g³ by an arm or projection g⁹, having a slot through which 40 passes a stop bolt g¹⁰ having a split adjusting nut g¹¹ which is firmly fixed in any position to which it may be turned by a set screw g¹²; the lever g³ having also an arm g¹² furnished 45 with a spring g¹³ interposed between said arm g¹² and the hinged and adjustable arm g⁷. The arm g¹² of the lever g³ is also furnished 50 with an adjusting screw g¹⁴ for further regulating the tension of the spring g¹³ and thus the yielding connection between the lever g³ and its hinged arm g⁷. Each of the seaming roller operating levers g² g³ is furnished 55 with an anti-friction roller g¹⁵, journaled upon a suitable stud g¹⁶ fixed in place by a set screw g¹⁷ for purpose of engagement with the rotary cam wheel H by which the several seaming rollers are operated or forced against the 60 seaming flanges of the can and cover to perform the seaming operation. The anti-friction rollers for engaging the cam which operates the seaming levers g³ is mounted upon
- the adjustable hinged arm g⁷ of the lever g³. The cam wheel H, carrying the cams h h¹ h² h³ for operating the several seaming roller levers is, preferably, for convenience of construction, formed in two separate pieces or 70 disks h⁴ h⁵, but as both these disks are rigidly and immovably secured to the same rotating sleeve or hollow shaft H¹ the operation is the same as if the two disks h⁴ h⁵ were in one piece. The cams h h¹ for operating the two 75 forming rollers g g are, preferably, formed on the lower disk h⁴ of the cam wheel H, and the two cams h² h³ for operating the two finishing rollers g¹, are preferably formed upon the upper disk h⁵ of the cam wheel H. The shaft 80 H¹ to which the cam wheel is secured preferably surrounds the hollow rotary shaft G¹, carrying the rotary seaming head G, and it is rotated at a speed slightly varying from that 85 of the seaming head, the cam wheel being rotated preferably at a speed slightly exceeding that of the rotary seaming head. This is preferably done by furnishing one of the gears through which motion is communicated to the cam wheel shaft with an additional tooth over the number in the corresponding gear through which motion is communicated to the rotary seaming head.
- K is a reciprocating can extractor disk, fitting in a recess E³ in the lower face of the upper chuck E, and operated by a reciprocating stem K¹ to eject or free the can from the chuck E after the seaming operation has 90 been completed.
- The required slow intermittent movement 95 is communicated to the can feeder C from the driving shaft M by a pulley m thereon; belt m¹, pulley m² on the rotary seaming head driving shaft P, having sprocket gear m³ thereon, chain m⁴, sprocket m⁵ on worm 100 shaft m⁶, having a worm m⁷ engaging a worm gear m⁸ on the shaft m⁹ which carries the bevel gear m¹⁰ meshing with the bevel gear m¹¹ on the shaft m¹², carrying an arm m¹³ carrying a roller m¹⁴, engaging a radially slotted 105 Geneva stop wheel m¹⁵ on the shaft m¹⁶, which carries the driving sprocket wheel C² of the can feeder C.
- The required vertically reciprocating movement is imparted to the lower reciprocating 110 can chuck D by a cam d on said shaft m¹², which engages a roller d¹ on the bell-crank, i.e. arm d² hinged to the frame at d³, and having a bifurcated arm d⁴, having studs d⁵ fitting in slots d⁶ in the sleeve f¹⁰ on the upright stem D¹ of the chuck D. A spring D² is interposed, 115 between the stem D¹ and the chuck D to give a yielding movement to compensate for slight variations in the height of the cans, the spring surrounding a pin D³.
- The can body clamping and centering jaws F, or their reciprocating slides F¹, are 120 opened and closed or reciprocated as required by means of rollers f⁹ on a sleeve f¹⁰ secured to the operating stem D⁴ of the chuck D, and

which rollers f^9 engage cam-faces f^{12} on the levers f^{13} which are connected at their upper ends to the slides F^1 , and which levers are pivoted to the frame at f^{14} .

5 The required continuous rapid rotary movement is communicated to the rotary seaming head G , or its shaft G^1 , from the shaft P by means of a bevel gear p on said shaft P , which meshes with a beveled gear G^2 10 on the shaft G^1 .

The required rotary motion is communicated to the cam wheel H or its shaft H^1 , by means of a gear p^1 on the shaft P , which meshes with a gear p^2 on the shaft P^1 , which 15 carries a bevel gear p^3 , which meshes with a bevel gear H^2 on the cam wheel shaft H^1 . The gear p^3 has one less tooth than the gear p^1 to cause the cam wheel shaft to rotate at a slightly greater speed than the rotary seaming head shaft. In practice I ordinarily 20 make the gear p^1 with 51 teeth and the gear p^2 with 50 teeth.

The can ejector disk K , or its stem K^1 , is preferably intermittently reciprocated as required by a cam K^2 on the shaft m^{12} engaging a lever K^3 , pivoted to the frame at K^4 , and connected to a rod K^5 connected with a lever K^6 pivoted to the frame at K^7 and connected to the stem K^1 of the ejector K . A spring K^8 connected at one end to the rod K^5 and the other to the frame of the machine holds the disk 30 normally in its upper or retracted position.

To adapt the machine to operate upon cans of different heights, the feed table B is 35 connected to or formed integral with a vertically movable slide B^{10} , which is secured to the frame A by a bolt B^2 , and which may be adjusted up and down as required by an adjusting screw B^3 threaded in the slide B^{10} , 40 and turning in the bracket A^1 of the frame A .

The vertically reciprocating lower chuck D is furnished with a slot or channel D^1 to receive the can feeder chain C and to enable the chuck D to move upward as required 45 without interfering with the feeder chain.

The seaming roller carrying levers g^2 g^3 are normally held in their open or retracted position by springs g^{18} interposed between said levers and the seaming head G .

50 In operation, the cans with the covers in place thereon, are placed on the feed table B and moved forward intermittently by the feeder C , and each thus delivered in turn on top of the lower reciprocating chuck D , the feeding chain pausing during the time necessary for operation upon each can. The chuck D then moves upward to clamp the can and its cover against the upper stationary chuck E , the segmental centering jaws F closing against the can bodies for centering the can with the chuck E , just before the chuck D forces the can against the chuck E . At the time the can is forced against the chuck D all the seaming rollers g^2 g^3 g^1 on the 55 rotary seaming head, are in their open or re-

tracted position to properly admit the can and its cover into the chuck E , the rapidly rotating seaming-roller-lever-operating cam wheel H being properly timed with the chuck D for this purpose. As soon as the can is properly clamped against the stationary chuck E by the reciprocating chuck D the accelerated rotary movement of the rapidly and continuously rotating cam wheel H , in respect to the rapidly and continuously rotat-

70

ing seaming head G , causes the cams h h^1 on the cam wheel H to begin to close the pair of forming rollers g g against the seaming flanges of the can cover and can body, and thus curl or fold said flanges together as the forming

75

rollers g g are rapidly rotated around the stationary can by the rotary seaming head, the forming rollers g g bearing more and more upon the can as the rotation continues.

80

After the forming rollers g g have thus been carried around the can a number of times, and the cover flange properly folded or curved over the can body flange, the further accelerating movement of the cam wheel, in respect to the rotary seaming head, causes

85

the finishing rollers g^1 g^1 to be forced against the seaming flanges of the can body and cover and the seaming operation thus finished or completed, the seaming rollers then

90

retract and the chuck D moves downward until its upper face is flush with the feed table B , and then the feeler C again moves forward and brings another can into position for

95

operation, when the operation is repeated.

I claim:

1. In a stationary can double seaming machine, the combination with a can feed table, of an intermittently movable can feeder, an intermittently reciprocating chuck upon which the cans are delivered one by one by the feeder, a pair of horizontally reciprocating can clamping jaws for clamping and centering the cans in position, an upper non-rotary can chuck, a continuously rotating seaming head carrying a plurality of seaming rollers, seaming roller operating levers hinged to the seaming head and upon which the seaming rollers are journaled, and a continuously rotating cam wheel furnished with cams for operating the seaming roller levers and rotating at a speed varying from that of the seaming head to cause the seaming rollers to open and close against the can at intervals, substantially as specified.

100

2. In a stationary can double seaming machine, the combination with a can feed table, of an intermittently movable can feeder, an intermittently reciprocating chuck upon which the cans are delivered one by one by the feeder, a pair of horizontally reciprocating can clamping jaws for clamping and centering the cans in position, an upper non-rotary can chuck, a continuously rotating seaming head carrying a plurality of seaming rollers, seaming roller operating levers hinged

105

110

115

120

125

130

135

- to the seaming head and upon which the seaming rollers are journaled, and a continuously rotating cam wheel furnished with cams for operating the seaming roller levers and rotating at a speed varying from that of the seaming head to cause the seaming rollers to open and close against the can at intervals, and a reciprocating can ejector disk in the stationary can chuck, substantially, as specified.
3. In a stationary can double seaming machine, the combination with a can feed table, of an intermittently movable can feeder, an intermittently reciprocating chuck upon which the cans are delivered one by one by the feeder, a pair of horizontally reciprocating can clamping jaws for clamping and centering the cans in position, an upper can chuck, a continuously rotating seaming head carrying a plurality of seaming rollers, seaming roller operating levers hinged to the seaming head and upon which the seaming rollers are journaled, and a continuously rotating cam wheel furnished with cams for operating the seaming roller levers and rotating at a speed varying from that of the seaming head to cause the seaming rollers to open and close against the can at intervals, said lower reciprocating can chuck having a slot or channel across the same to receive or accommodate the can feeder, substantially as specified.
4. In a stationary can double seaming machine, the combination with a pair of non-rotatable chucks for clamping and holding the can and its cover, of a continuously rotating seaming head furnished with seaming rollers and seaming roller levers extending lengthwise of said seaming head and hinged thereto, a continuously rotating cam wheel having an axis concentric with that of the seaming head and rotating at a different speed from the seaming head to cause the cams on the cam wheel to operate the seaming roller levers at intervals, as required, substantially as specified.
5. In a stationary can double seaming machine, the combination with a pair of non-rotatable chucks for clamping and holding the can and its cover, of a continuously rotating seaming head furnished with seaming rollers and seaming roller levers extending lengthwise of said seaming head and hinged thereto, a continuously rotating cam-wheel having an axis concentric with that of the seaming head and rotating at a different speed from the seaming head to cause the cams on the cam-wheel to operate the seaming roller levers at intervals, as required, and a reciprocating can ejector disk in the upper can chuck, substantially as specified.
6. In a stationary can double seaming machine, the combination with a pair of non-rotatable chucks for clamping and holding the can and its cover, of a continuously rotating seaming head furnished with seaming
- rollers and seaming-roller-levers, a continuously rotating cam wheel having an axis concentric with that of the seaming head and rotating at a different speed from the seaming head to cause the cams on the cam wheel to operate the seaming rollers at intervals as required, a can feed table and an endless flexible can feeder, the lower can chuck having a slot or channel to receive and accommodate the upper run of the endless flexible can feeder, substantially as specified.
7. In a stationary can double seaming machine, the combination with a pair of non-rotatable chucks for clamping and holding the can and its cover, of a continuously rotating seaming head furnished with seaming rollers and seaming-roller-levers, a continuously rotating cam wheel having an axis concentric with that of the seaming head and rotating at a different speed from the seaming head to cause the cams on the cam wheel to operate the seaming rollers at intervals as required, a can feed table and an endless flexible can feeder, the lower can chuck having a slot or channel to receive and accommodate the upper run of the endless flexible can feeder, and the feed table having a channel to receive and accommodate said upper run of said endless flexible can feeder, substantially as specified.
8. In a stationary can double seaming machine, the combination with a pair of non-rotatable chucks for clamping and holding the can and its cover, of a continuously rotating seaming head furnished with a pair of forming seaming rollers and levers for operating the same, and a pair of finishing rollers and levers for operating the same, said finishing roller levers having additional yielding and adjustable hinged arms, and a continuously rotating cam wheel having an axis concentric with that of the rotary seaming head and rotating at a variant speed from that of the seaming head, substantially as specified.
9. In a stationary can double seaming machine, the combination with a pair of non-rotatable chucks for clamping and holding the can and its cover, of a continuously rotating seaming head furnished with a pair of forming seaming rollers and levers for operating the same, a pair of finishing rollers and levers for operating the same, said finishing roller levers having additional yielding and adjustable hinged arms, a continuously rotating cam wheel having an axis concentric with that of the rotary seaming head and rotating at a variant speed from that of the seaming head, and a pair of horizontally reciprocating can body-clamping and centering jaws, substantially as specified.
10. In a stationary can double seaming machine, the combination with a pair of non-rotatable chucks for clamping and holding the can and its cover, of a continuously rotating seaming head furnished with seaming

- rollers and seaming roller levers, a continuously rotating cam wheel having an axis concentric with that of the seaming head and rotating at a different speed from the seaming head to cause the cams on the cam wheel to operate the seaming roller levers at intervals as required, and a pair of horizontally reciprocating can body clamping and centering jaws, substantially as specified. 5
11. In a stationary can double seaming machine, the combination with a pair of non-rotatable chucks for clamping and holding the can and its cover, of a continuously rotating seaming head furnished with seaming rollers and seaming roller levers, a continuously rotating cam wheel having an axis concentric with that of the seaming head and rotated at a different speed from the seaming head to cause the cams on the cam wheel to operate the seaming roller levers at intervals as required, a pair of horizontally reciprocating can body clamping and centering jaws and a can feeder, substantially as specified. 15
12. In a stationary can double seaming machine, the combination with a pair of non-rotatable chucks for clamping and holding the can and its cover, of a continuously rotating seaming head furnished with seaming rollers and seaming roller levers, a continuously rotating cam wheel having an axis concentric with that of the seaming head and rotating at different speed from the seaming head to cause the cams on the cam wheel to operate the seaming roller levers at intervals as required, a pair of horizontally reciprocating can body clamping and centering jaws, and a reciprocating can ejector in the upper can chuck, substantially as specified. 20
13. In a stationary can double seaming machine the combination with a pair of non-rotatable chucks for clamping and holding the can and its cover, of a continuously rotating seaming head furnished with seaming rollers and seaming roller levers, a continuously rotating cam wheel having an axis concentric with that of the seaming head and rotating at different speed from the seaming head to cause the cams on the cam wheel to operate the seaming roller levers at intervals as required, a pair of horizontally reciprocating can body clamping and centering jaws, and a reciprocating can ejector in the upper can chuck, substantially as specified. 25
14. In a stationary can double seaming machine, the combination with a pair of non-rotatable chucks for clamping and holding the can and its cover, of a continuously rotating seaming head furnished with seaming rollers and seaming roller levers, a continuously rotating cam wheel having an axis concentric with that of the seaming head and rotating at a different speed from the seaming head to cause the cams on the cam wheel to operate the seaming roller levers at intervals as required, and a pair of horizontally reciprocating can body clamping and centering jaws, a can feed table furnished with a central longitudinal channel and with a central opening for the lower can chuck to reciprocate through, and an endless flexible can feed chain having its upper run fitting and moving in the channel of the can feed table, substantially as specified. 30
15. In a stationary can double seaming machine, the combination with a pair of non-rotatable chucks for clamping and holding the can and its cover, of a continuously rotating seaming head furnished with seaming rollers and seaming roller levers, a continuously rotating cam wheel having an axis concentric with that of the seaming head and rotating at different speed from the seaming head to cause the cams on the cam wheel to operate the seaming roller levers at intervals as required, a pair of centering jaws, a reciprocating can ejector in the upper can chuck, a can feed table furnished with a central longitudinal channel and with a central opening for the lower can chuck to reciprocate through, an endless flexible can feed chain having its upper run fitting and moving in the channel of the can feed table, said lower can chuck having a slot or channel across the same to accommodate the upper run of said feed chain, substantially as specified. 35
16. In a stationary can double seaming machine, the combination with a pair of non-rotatable chucks for clamping and holding the can and its cover, of a rotary seaming head furnished with a plurality of seaming rollers and seaming roller levers extending lengthwise of said seaming head and hinged thereto, a rotary cam wheel having a plurality of cams for operating said seaming roller levers, means for rotating the seaming head and means for rotating the cam wheel at a different speed from that of the seaming head to cause the cams on the cam wheel to operate the seaming roller levers, substantially as specified. 40
17. In a double seaming machine, the combination with a pair of chucks for clamping the can and its cover, of a rotary seaming head furnished with seaming rollers and vertically swinging seaming roller levers extending lengthwise of said seaming head and hinged thereto, a rotary cam wheel for operating said seaming roller levers, means for rotating the seaming head and means for rotating the cam wheels at a variant speed from that of the seaming head, substantially as specified. 45

18. In a seaming machine, the combination with a pair of non-rotatable chucks for clamping and holding the can and its cover, of a rotary seaming head furnished with 5 seaming rollers and seaming roller levers extending lengthwise of the seaming head and hinged thereto, and a rotary cam wheel

rotating at a different speed from the seaming head for operating the seaming rollers, substantially as specified.

FRANK RUDOLPHI.
